GRINDING MACHINE

Mischa N. Berezny, San Francisco, Calif.

Application October 29, 1943, Serial No. 508,127

7 Claims. (Cl. 51—241)

This invention relates to grinding machines and more particularly to grinding apparatus designed to work on flat annular surfaces and to reduce such to an even plane.

The main object of the invention is to provide a simple, compact, and portable mechanism for grinding the contacting faces of annular flanges such as employed on steel pipe for connecting the sections thereof. It is essential that such faces be ground to an even plane to assure leakless joints, particularly where high pressure steam is to be conveyed, and it has heretofore been the practice to grind down the faces of the pipe flanges by hand. The invention embodied in the mechanism hereinafter described enables the grinding to be quickly and accurately accomplished by a unit adapted to be clamped directly to the pipe flange and to automatically effect the grinding operation when so connected and adjusted to engage the work surface.

A preferred form of the invention is more specifically described herein and is illustrated in the accompanying drawings where,

Figure 1 is a side elevation of the grinding unit with certain parts shown in section,

Figure 2 is a plan view thereof, and Figure 3 is an end elevation.

The unit is shown in connection with the end of a pipe 10 having the circular end flange 11 formed with the annular contacting face 12 which constitutes the surface to be ground.

The unit is designed to be clamped to and wholly supported by the pipe 10 through clamping means engaging the peripheral edge of the flange 11. Accordingly, the unit comprises opposed chuck heads 13 preferably shaped as shown in Figure 2, and formed with V-grooves at 14 for engagement with the flange edge. Each chuck head 13 has a pair of upwardly and inwardly extended annular chuck arms 15 secured thereto with the respective inwardly extended portions of the arms on the opposite heads in alignment and inwardly screw threaded. The ends of the opposite pairs of arms receive the screw threaded ends of adjusting screw shafts 16 which are journaled in opposite lateral projections 17 of the supporting frame or body of the grinder. The projections 17 are spaced to accommodate the nuts 18 on the screw shafts for turning same when mounting or dismounting the unit as it will be evident that rotation of the shafts 16 will effect movement of the chuck heads 13.

The driving and grinding elements are supported in a frame comprising the horizontal bed piece 19, with which the arms 17 are preferably integral, and the upright arched plate number 20 (Fig. 3). The bed piece 19 is open at the center to receive the cylindrical drive block 21 (Fig. 1). This drive block constitutes the tool

carrying member of the machine and extends below the bed piece 19 where it is formed with male threads for connection with mating threads, at 22, in the inner portion of a horizontal grinder carrying arm 23. The drive block 21 is surrounded by a sleeve 24 rotatable on the block, and mounted between the annular flange 25 on the lower portion of the block 21 and the horizontal gear 26 secured to the upper face of the block as by bolts 27. The upper portion of block 21 is threaded as shown at 28 and is engaged by the adjusting ring 29 having complementary threads. Ring 29 is formed with an annular rack at 30 in mesh with a pinion 31 keyed to a shaft 32 mounted on the bed piece 19 and provided with a hand wheel 33. Actuation of shaft 32 will serve to rotate ring 29 with consequent adjustment of drive block 21 vertically to raise and lower the grinder carrying arm 23. The arm 23 is longitudinally slotted to slidably receive the grinder carriage 34. This carriage has a longitudinal threaded bore through which passes the threaded shaft 35 rotatably mounted in the slot of arm 23 with its outer end extended a little beyond this arm and provided with a star shaped cam 36 the arms of which are positioned to engage a vertically adjustable trip 37. The carriage 34 is formed with aligned depending lugs 38 in which the grinder roll drive shaft 39 is mounted for rotation. This shaft is angular in section, or splined, and a grinder roll 40 is slidably mounted on it between the lugs 38. At its inner end shaft 39 is rotatably supported in a bearing bracket 41 against longitudinal movement and has the bevel pinion 42 secured to its adjacent the bracket. Pinion 42 is in mesh with a bevel pinion 43 on the lower end of a hollow vertical drive shaft 44 of angular cross section, which telescopes an upper section 44a directly driven by an electric motor 45 mounted on the arched member 20. Shaft 44 extends through a central bore 46 in drive block 21 and through bearing sleeves 47, 48 which are rotatable in the bore. This arrangement permits the required vertical adjustment of the drive block and grinder arm and imparts rapid rotation to the grinder roll 40.

To move the grinder roll in an orbital path over the flange face 12 at a low speed, the upper section 44a of the vertical drive shaft carries a drive gear 49 which rotates with the shaft and is vertically shiftable on it for a purpose to be described. The drive gear 49 is normally in mesh with a larger intermediate gear 50 journaled on a normally vertical shaft the lower end of which is pivotally supported at 51 on the bed piece 19 and the upper end shiftable clamped in a slot in an arcuate laterally extending arm 52 on arched member 20, as by a screw nut 53. Below gear 50 and rotatable with it as a unit is a gear sleeve 54 of small diameter and positioned to be nor-

mally in mesh with gear 26 of the drive block. The gear train just described obviously will impart a slow rotary movement to the block 21 and the grinder arm and roll it carries thus moving the rapidly rotating grinder roll slowly over the flange surface. The elongated gear sleeve 54 is provided to permit the vertical adjustment of the grinder mechanism heretofore referred to. At each revolution of the grinder arm, the star wheel 36 will contact the trip 37 and the threaded shaft 35 be rotated approximately a quarter revolution, thus causing successive slight radial movements of the grinder roll.

To provide for a modified use of the grinder mechanism, as for instance grinding or lapping the inner surface or end of a pipe length, the drive gear 49 is provided with a shift collar 55 mounted in the fork of a shift lever 56 (Fig. 3) pivoted horizontally to one arm of the arched member 20 at 57 and having a handle 58 on its free end beyond the opposite arm. Gear 26, directly below drive gear 49, is formed with a central, internally toothed, opening 59 adapted to interlock with drive gear 49. When gear 50 and sleeve 54 are moved out of mesh with gears 26 and 49 by tilting them, as shown in dotted line position in Fig. 1, and gear 49 is shifted into interlocked position with gear 26, a direct drive will be imparted to the drive block 21 to rotate it at rapid rate. The screw thread connection between this block and the grinder arm at 22 allows the arm to be removed and some other grinding or lapping tool substituted.

The specific structure described is illustrative of the invention but is capable of variations without departure therefrom as hereinafter claimed.

I claim:

1. A portable grinder of the class described comprising a bed piece, opposite chuck heads mounted for radial clamping movement relatively to the bed piece in offset relation thereto and adapted to engage the edges of a pipe flange to position the bed piece in spaced relation to the flange face, a centrally located carrier head rotatable on the bed piece, a radial tool carrying arm extending from the carrier below the bed piece in fixed relation thereto, a grinder roll on said arm adapted to contact a flange face and means on the bed piece for driving the grinder roll and for simultaneously rotating the carrier head to move the grinder roll in an orbital path.
2. A portable grinder of the class described comprising a bed piece, opposite chuck heads mounted for radial clamping movement relatively to the bed piece in offset relation thereto and adapted to engage the edges of a pipe flange to position the bed piece in spaced relation to the flange face, a centrally located carrier head rotatable and axially adjustable on the bed piece, a radial tool carrying arm extending from the carrier below the bed piece in fixed relation thereto, a grinder roll on said arm adapted to contact a flange face, means on the bed piece for adjusting the carrier head axially to and from the work, and means carried by the bed piece for driving the grinding roll and for simultaneously rotating the carrier head to move the grinder roll in an orbital path.
3. In a grinding machine, a rotatably mounted tool carrier and gear wheel rotatable as a unit and having an axial bore, a drive shaft located in said bore, means for rotating the drive shaft at constant speed, an axially shiftable drive pinion splined on the drive shaft adjacent the car-

rier, a countershaft mounted adjacent the carrier and parallel to the drive shaft, intermediate reduction gears on the counter shaft normally in mesh with the drive gear and with the carrier gear wheel, and means for shifting the drive gear from engagement with the counter shaft gears and into interlocking engagement with the carrier.

4. In a grinding machine, a rotatably mounted tool carrier and gear wheel rotatable as a unit and having an axial bore, a drive shaft located in said bore, means for rotating the drive shaft at constant speed, an axially shiftable drive pinion splined on the drive shaft adjacent the carrier, a laterally shiftable counter-shaft mounted adjacent the carrier and parallel to the drive shaft, intermediate reduction gears on the counter-shaft normally in mesh with the drive gear and with the carrier gear wheel, means for moving the counter-shaft from engagement with said gears by shifting same laterally and means for shifting the drive gear into interlocking engagement with the carrier.

5. In a grinding machine, a rotatably mounted tool carrier and gear wheel rotatable as a unit and having an axial bore, a drive shaft located in said bore, a grinder shaft on the carrier extending radially from the drive shaft and geared thereto, a grinding roll splined on the grinder shaft means for rotating the drive shaft at constant speed, an axially shiftable drive pinion splined on the drive shaft adjacent the carrier, a laterally shiftable counter-shaft mounted adjacent the carrier and parallel to the drive shaft, intermediate reduction gears on the counter-shaft normally in mesh with the drive gear and with the carrier gear wheel, means for moving the counter-shaft from engagement with said gears by shifting same laterally and means for imparting successive increments of movement to the grinding roll along its shaft.

6. In a grinding machine, a tool carrier and gear wheel mounted for rotation as a unit and having an axial bore, a drive shaft located in said bore and having a tool driving element on its end beyond the carrier, means for driving the shaft, a tool arm extending radially from the carrier adjacent the tool driving element, a grinding roll carried by said arm and rotatable with a shaft extending parallel to said arm and in direct driving relation with said element, and means actuated by the drive shaft for simultaneously rotating the carrier at reduced speed to move said roll in an orbital path.

7. In a grinding machine, a tool carrier and gear wheel mounted for rotation as a unit and having an axial bore, a drive shaft located in said bore and having a tool driving element on its end beyond the carrier, means for driving the shaft, a tool arm extending radially from the carrier adjacent the tool driving element, a threaded shaft mounted on said arm parallel thereto, a tool carriage movable on the threads of said shaft, a grinding roll on said carriage and rotatable with a shaft extending parallel to said arm and in direct driving relation with said element, means actuated by the drive shaft for simultaneously rotating the carrier at reduced speed to move said roll in an orbital path, and tripping means in the path of said tool arm positioned to engage an actuating means on the threaded shaft to impart successive partial rotations thereto thereby moving the grinding roll step by step along its actuating shaft.

MISCHA N. BEREZNY.
